BOILER

Isaac Harter, New York, N. Y., assignor to The Babcock & Wilcox Company, Bayonne, N. J., a corporation of New Jersey

Application July 22, 1929, Serial No. 380,172

5 Claims. (Cl. 122—265)

This invention relates to a novel and improved form of boiler, the novel features of which will be best understood from the following description and the annexed drawings, in which I have shown a selected embodiment of the invention and in which:

Fig. 1 is a vertical sectional view through a boiler having my invention embodied therein.

Fig. 2 is a view taken on the line 2—2 of Fig. 1. 10 Fig. 3 is a section on the line 3—3 of Fig. 1.

Figs. 4 and 5 are sectional details on lines 4—4 and 5—5 of Fig. 3.

Referring first to Fig. 1, the invention is shown as embodied in a boiler disposed above a combustion chamber 1, in the walls of which are water tubes 2 connected to the circulating system of the boiler, this particular furnace being heated by means of pulverized fuel, and part of one burner being shown at 3. Above the furnace 20 is placed a plurality of tubes 4 preferably curved on the arcs of concentric circles and connected at their ends to headers 5 and 6, it being noted that the tubes enter the headers substantially normal thereto. Above the tubes 4 is shown a superheater 7. The downtake headers 6 are connected to a steam and water drum 8 by means of nipples 9, while nipples 10 connect the steam drum to the uptake headers 5. It will be seen that the headers 5 and 6 form between them a 30 tapered gas pass, through which gases flow over the tubes and the superheater to the gas outlet 11.

Referring now to Figs. 2 and 3, it will be seen that the boiler is formed of a plurality of sections placed side by side, each section including an uptake and a downtake header connected by a single row of tubes extending lengthwise of the headers. The headers are relatively narrow rectangular shaped boxes placed side by side and 40 closely adjacent each other, so as to define the opposite sides of the gas pass and the single row of tubes having their ends received in holes disposed substantially centrally of the flat walls of the headers which face the pass. These walls 45 are plain and, when headers having circular cross section are used, the walls of the headers constituting the tube seat faces are rounded. The illustrative headers of rectangular cross section, of course, have flat faces, but it is to be appreciated that the invention is of such a scope that it covers fluid heat exchange apparatus in which the header portions forming the tube seat faces are rounded. In either case, the headers may be described as having plain sides when they do 55 not have forged or upset portions so that adja-

cent tube seat faces will be at an angle to each other. The lower tubes 4' which with the others are curved lengthwise of the headers, have their axes disposed substantially in the plane passing through the axes of the two headers in the section, whereas the tubes 4 are swung on their ends so that the major portions of the tubes are disposed some on one side and some on the other side of such a plane, thus giving the staggered effect which will be apparent from Fig. 2.

The amount of the swinging is preferably such that the approximate quarter points 12 of any one tube are disposed substantially midway between the tubes in an adjacent row extending transversely of the boiler. This gives a staggered effect while permitting the use of relatively narrow boxes as headers. These boxes may be provided with the usual handholes and fittings therefor indicated at 13, and by means of which access to the tubes may be had.

The holes in a header within which the tube ends are received, are preferably bored normally to the surface of the header, but with sufficient clearance so that the tubes may be swung in the holes to their desired positions. The tube ends 80 may then be expanded into the holes in the usual way.

I claim:—

1. In a water tube boiler, two groups of headers inclined to each other, the headers in each group being placed side by side and having substantially plain sides facing the headers in the other group, a single row of tube holes extending lengthwise of each header, and a row of curved tubes having their opposite ends secured 90 in holes in opposite headers, the adjacent tubes connected to the same header having their planes of curvature oblique to each other to produce a tube bank in which the tubes are in staggered arrangement.

2. In a water tube steam boiler, a furnace, a steam and water drum, headers mounted in divergent relationship, and a bank of curved water tubes extending transversely of a gas pass leading from the furnace and connected to the 100 headers and indirectly to the drum to form a natural circulation boiler, the curved tubes most remote from the drum being arranged in rows parallel to the gas flow and having their axes each positioned in a plane normal to the axis of the 105 drum while successive curved tubes forming that part of the bank nearer to the drum are swung alternately in opposite directions to position their axes in individual planes oblique to the drum axis whereby the upper part of the tube bank 110

has its tubes in staggered arrangement without involving undulating headers or additional bending of the tubes for the sole purpose of producing that staggered arrangement.

5. 3. In a steam generator, opposite divergent headers provided with facing tube seats, and concentrically curved tubes connecting the opposite headers and positioned in the tube seats, some of the successive tubes being positioned in superposed relationship in parallel rows and alternate tubes of the remainder of the tubes being rotated in position in their seats in opposite directions to thereby throw the latter into staggered relation with respect to each other.
10. 4. In a water tube boiler, two groups of headers, each group disposed on one side of a tapered gas pass with the headers therein extending in the direction of gas flow, the headers in each group having their sides facing the gas pass parallel to their longitudinal axes and having plane faces provided with tube seats, tubes connected to headers in opposite groups and extending across the pass, said tubes being arranged in rows transversely of the pass and having their 25. ends received in holes arranged in rows extend-

ing lengthwise of the pass, each tube being bent and arranged with its convex side toward the inlet end of the pass, the adjacent tubes connected to the same header having their planes of curvature oblique to each other to produce a tube bank 80 in which the tubes are in staggered arrangement, the tube seats in an individual header having parallel axes.

5. In a water tube boiler, upwardly convergent header constructions disposed on opposite sides of a tapered gas pass and extending in the direction of gas flow, the headers having plane faced sides facing the gas pass and provided with tube seats, tubes connected to the headers and extending across the pass, said tubes being arranged in rows transversely of the pass and having their ends received in tube seats arranged in rows extending lengthwise of the pass, each tube being bent and arranged with its convex side towards the inlet end of the pass, the adjacent tubes connected to the same header having their planes of curvature oblique to each other to produce a tube bank in which the tubes are in staggered arrangement. 85 90 95
